UNITED STATES PATENT OFFICE

165,037

HOOD ORNAMENT

Herbert F. Weissinger, Franklin, and William B. Kindred, Allen Park, Mich., assignors to Kaiser-Frazer Corporation, Willow Run, Mich., a corporation of Nevada

Application June 22, 1951, Serial No. 15,628

Term of patent 14 years

(Cl. D14—18)

To all whom it may concern:

Be it known that we, Herbert F. Weissinger and William B. Kindred, citizens of the United States of America, and residents, respectively, of the city of Franklin, county of Oakland, State of Michigan, and city of Allen Park, county of Wayne, State of Michigan, have invented a new, original, and ornamental Design for Hood Ornament, of which the following is a specification, reference being had to the accompanying drawing, forming a part thereof, wherein:

Fig. 2 is a side elevational view of the hood ornament illustrated in Fig. 1;

Fig. 3 is a front elevational view of the hood ornament shown in Fig. 2, as viewed from the left thereof; and

Fig. 4 is a cross-sectional view, taken substantially along the line 4—4 of Fig. 2.

We claim:

The ornamental design for a hood ornament, as shown.

HERBERT F. WEISSINGER.
WILLIAM B. KINDRED.
